UNITED STATES PATENT OFFICE.

THEODORE E. DRUMMOND, OF FORT SMITH, ARKANSAS, ASSIGNOR OF ONE-HALF TO
THEOPHILUS H. McCLINTON, OF FORT SMITH, ARKANSAS.

CUP-LEATHER EXPANDER.

1,412,231.

Specification of Letters Patent. Patented Apr. 11, 1922.

Application filed April 18, 1921. Serial No. 462,361.

To all whom it may concern:

Be it known that I, THEODORE E. DRUMMOND, a citizen of the United States, residing at Fort Smith, in the county of Sebastian and State of Arkansas, have invented certain new and useful Improvements in Cup-Leather Expanders, of which the following is a specification, reference being had to the accompanying drawings.

10 This invention relates to improvements in cup leather expanders and has for an important object thereof the provision of an expansion ring for expanding the cup leather of pumps and the like, when the flanges thereof shall have become so worn in use that they become inefficient.

15 A further object of the invention is to provide a device of this character which may be very cheaply produced and very readily applied.

20 A still further object of the invention is to provide a device of this character which is held in position by a follower plate employed for securing the cup leather to the piston.

25 Other objects and advantages of the invention will become apparent throughout the course of the following description.

30 In the accompanying drawings wherein for the purpose of illustration is shown a preferred embodiment of my invention and wherein like reference characters designate like parts throughout:

35 Figure 1 is a longitudinal sectional view taken through a piston and cylinder showing a leather expander constructed in accordance with my invention applied thereto;

40 Figure 2 is a similar view, the expander being shown in elevation;

45 Figure 3 is a plan view of the follower plate and expander removed, the expander being shown in the position normally assumed thereby;

50 Figure 4 is a similar view showing the expander in the position assumed when the same is placed within the flange of the cup leather;

55 Figure 5 is a section on the line 5—5 of Figure 3;

Figure 6 is a section on the line 6—6 of Figure 4; and

Figure 7 is a section on the line 7—7 of Figure 4.

Referring now more particularly to the drawings, R designates the piston rod of

a pump, and P the piston thereof mounted for reciprocation within the cylinder C in the usual manner. The character L designates a cup leather which is held against the piston P by follower plate F, adjustable 60 through the medium of a nut N upon the piston rod R. The direction above referred to is a common one employed in pumps of various descriptions as well as in air motors and similar devices.

65 In accordance with my invention, the follower plate F is provided with a substantially radial extension 10 embodying an angular portion 11 spaced from the center of the follower plate F a distance substantially equal to the internal radius of the cup leather L. The numeral 12 designates a ring formed of spring metal centrally slotted, as at 13, to divide the same into a plurality of sections 14 which are oppositely 70 swaged, the alternate sections 14 being bent inwardly and outwardly to provide therebetween a space permitting the ready insertion of the angular portion 11 of the follower plate extension 10. When the ring 75 12 is applied in position the end 11^a of the extension is bent back upon the ring to prevent displacement thereof, the ring is thus held inwardly of the flange of the cup leather and expands against the inner surface of such flange. One of the ends of the ring 12 is provided at the sides thereof with tabs 15 which are bent back upon the inner face of the ring to provide a guide for the opposite end of the ring, which is reduced as indicated at 16. The engagement 80 between the tabs 15 and the reduced end 16 is such as to permit the end 16 to slide readily with relation to the end bearing the tabs in order that the ring may at all times tend 85 to move outwardly and thereby force the flange of the cup leather into engagement with the walls of the cylinder.

90 From the foregoing it is believed to be obvious that I have constructed a cup leather expander which is particularly well adapted for the use for which it is intended by reason of the fact that it may be very cheaply produced and readily attached, and will at the same time perform its function. 95 It will furthermore be obvious that the construction of the same as hereinbefore set forth is capable of some change and modification without departing from the spirit of my invention, and I accordingly do not 100 105 110

limit myself to the specific structure thereof except as hereinafter claimed.

What I claim is:

1. The combination with a piston rod and piston, a cup leather having the convex face thereof abutting the piston through which said rod extends, and a clamping disk upon the rod and abutting the concave face of the leather, of an integral radial extension formed upon the said disk and provided with an angular portion arranged adjacent the flange of said cup leather, and an expandible split ring centrally secured to said angular portion, the ends of said ring overlapping and being connected for relative sliding movement, said ring abutting the inner face of the flange of the cup leather to force the same outward.
2. The combination with a piston rod and piston, a cup leather having the convex face thereof abutting the piston through which said rod extends, and a clamping disk upon the rod and abutting the concave face of the leather, of an integral radial extension formed upon said disk and embodying an angular portion extending adjacent the inner surface of the flange of the cup leather, a split ring having slits formed therein approximately centrally thereof, said slits extending longitudinally of the ring and dividing the central portion thereof into a

plurality of sections, said sections being oppositely bent to afford therebetween a space for the reception of the angular portion of said extension, the end of such angular portion overlapping and engaging the ring to prevent displacement thereof.

3. The combination with a piston rod and piston, a cup leather having the convex face thereof abutting the piston through which said rod extends, and a clamping disk upon the rod and abutting the concave face of the leather, of an integral radial extension formed upon said disk and embodying an angular portion extending adjacent the inner surface of the flange of the cup leather, a split ring having slits formed therein approximately centrally thereof, said slits extending longitudinally of the ring and dividing the central portion thereof into a plurality of sections, said sections being oppositely bent to afford therebetween a space for the reception of the angular portion of said extension, the end of such angular portion overlapping and engaging the ring to prevent displacement thereof.

In testimony whereof I hereunto affix my signature.

THEODORE E. DRUMMOND.
